CLAIM

I claim the ornamental design for a nail and skin abrasion device, as shown and described.

DESCRIPTION

FIG. 1 is a top, front perspective view of an embodiment of the claimed design;

FIG. 2 is a top, rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The ornamental design which is claimed is shown in solid lines in the drawings. The broken lines illustrate the environment and form no part of the claimed design.
